BOAT

Herbert M. Piker, 611 Hickory Hill Lane, Wyoming,
Ohio 45215, and Otis C. Borum, Deb Apartments,
Apt. 503, 4070 Barnes St., Jacksonville, Fla. 33216

Filed Sept. 9, 1970, Ser. No. 24,897

Term of patent 14 years

Int. Cl. D12—06

U.S. Cl. D71—1

223,219

FIG. 1 is a side elevational view of a boat showing our new design.

FIG. 2 is a top plan view of the boat as shown in FIG. 1.

FIG. 3 is an end elevational view of the boat shown in FIGS. 1 and 2.

FIG. 4 is a rear view of the boat as shown in FIGS. 1 and 2.

We claim:

The ornamental design for a boat, substantially as shown and described.
